UNITED STATES PATENT OFFICE.

CHARLES COURTOIS, OF VOLCANO, CALIFORNIA.

IMPROVEMENT IN ROCK-DRILLS.

Specification forming part of Letters Patent No. 40,020, dated September 22, 1863.

To all whom it may concern:

Be it known that I, CHARLES COURTOIS, of Volcano, in the county of Amador and State of California, have invented a new and useful Improvement in Rock-Drills; and I do hereby declare that the following is a full, clear, and exact description of the same, reference being had to the accompanying drawings, forming a part of this specification, in which—

Figure 1 represents a front elevation of my drill. Fig. 2 is a side elevation of the same. Fig. 3 is a plan or top view of the die for sharpening the drill. Fig. 4 is a vertical central section of the same.

Similar letters of reference indicate corresponding parts in the several figures.

This invention relates to the peculiar shape of the drill, and to the die which serves to sharpen the same.

By referring to the drawings it will be noticed that my drill A is constructed with a stem or shank, a, to which the head b is rigidly attached. This head is square, and it bevels from the top down toward the end. The cutting-edge c is about one-third the width of the face of the square at the top, and the bevel varies according to the hardness of the rock.

For soft work the angle of the cutting-edge can be made sharper than for hard rock, which requires a blunt or obtuse bevel.

The sides of the head b are concave, as indicated in the die in Fig. 3, where the cavity d represents the counterpart of the head of the drill.

By having the sides of the head concave the sharpening of the drill is considerably

facilitated, and it cuts much easier and quicker than a drill of the ordinary shape; and, furthermore, my drill will work twice as long or more than an ordinary drill before it requires to be sharpened.

B represents the die which I use for sharpening my drill. The cavity d in the die corresponds to the shape of the head b, and if the drill is to be sharpened the head is heated and driven down into the die.

The edges of the head are thereby forced into the corners of the cavity, and the faces of the head become concave by the action of the convex sides of the cavity, and at the same time the cutting-edge will become sharp, so that it requires but very little hammering when taken from the die.

By the use of this die the operation of sharpening my drill can be accomplished in a short time, and, besides the saving in time by the use of the die, a great saving in steel is effected.

What I claim as new, and desire to secure by Letters Patent, is—

A drill A, having its head b formed square and beveling with concave sides, and the cutting-edge c about one-third the width of the face of the square, as shown and described; also, the employment or use of the die B with a cavity, d, corresponding to the shape of the head b, as described, for the purpose of sharpening the drill A.

CHARLES COURTOIS.
